SOUND POST FOR VIOLINS

Filed April 21, 1927

FIG.1

FIG.2

FIG.5

FIG.3

FIG.4

FIG.6

Ralph W. Stephenson, ^{INVENTOR.}
BY Walter N. Haskell.

his ATTORNEY.

UNITED STATES PATENT OFFICE.

RALPH W. STEPHENSON, OF DAVENPORT, IOWA.

SOUND POST FOR VIOLINS.

Application filed April 21, 1927. Serial No. 185,371.

My invention has reference to sound-posts for violins and other stringed instruments, and has for its purpose to improve the action of such instruments, resulting in an increase 5 in the number of overtones, more mellow tones, and tones of greater power and penetrating quality. It does not attempt to displace any of the well-known and tried principles of harmonics as applied to such instruments, but serves to give added strength and life thereto.

The usual sound-post of a violin has for its purpose to control the vibrations of the strings, and assist in holding the bridge of the instrument in a state of rest. These it does but imperfectly, and the purpose of the present invention is to render the function of the sound-post more effective, to the extent of greatly changing the character of the instrument. This it does by providing the sound-post with an auxiliary vibratory device, capable of transmitting a multiplicity of tones, and thereby increasing the volume and sweetness of all of the tones. It does this without any noticeable encroachment upon the "violin" air, and in no way mutes the tones of the instrument.

The above named, and other features and advantages of the invention will be more fully understood from the following specification, taken in connection with the accompanying drawings, in which:

Fig. 1 is a cross-section through the body of a violin, near the bridge mounted thereon.

Fig. 2 is a fragmentary longitudinal section of an instrument, also in the vicinity of the bridge.

Fig. 3 is an enlarged side view of the invention, detached.

Fig. 4 is an upper end view thereof.

Fig. 5 is a lower end view thereof.

Fig. 6 is a detail of the post 5.

The reference number 1 indicates the sounding-board of a violin, and 2 the back thereof, said parts being united at their edges by side-pieces 3. Mounted on the sound-board 1 is a bridge 4, and secured between said sound-board and the back 2 in the vicinity of the bridge 4 is a sound-post 5, to which is fixed a spiral lamina 6, of gradually increasing radius upwardly. Said lamina is preferably attached to the post by means of a spiral channel 7 in the post to receive the inner edge of the lamina. Other methods of attachment may be employed, however, and the post and lamina may be formed in a sin-

gle piece. Said parts are both preferably formed of wood of a kind best adapted to the purpose, but other materials may be substituted for one or both of said parts.

The best results are found to be secured by giving the lamina a winding of approximately two and one-half times around the post, ending in a radial edge 8 at its widest part, the extreme end of said lamina being reduced to the thinness of the blade of a knife.

There is a marked similarity between the form of the lamina 6 and the lamina spiralis ossea of the cochlea of the human ear, the membranes of which are given a winding of two and one-half turns about a stem or modiolus of bone, with which the sound-post 5 compares. Associated with the lamina spiralis of the ear is the scala media, supposed to be the sound classifier, which assists in separating the musical tones from the more inharmonious sounds and noises. It determines the range of the tones and overtones, and it is believed that the operation of the present invention is largely similar to that of the parts just mentioned.

The spirals of the lamina 6 lie in substantially parallel position between the upper and lower boards of the violin, winding about the post 5 as a modiolus and affecting the vibrations thereof, producing more overtones, rendering the tones more mellow, and giving them greater power and penetrating quality.

In the embodiment set forth herein the pitch of the spirals is shown as about equal to the diameter of the post 5, but this pitch may be varied at will, so as to produce the best results, and the lamina may be placed on the post in an inverted position, or otherwise positioned thereon. The winding of the spiral may be the opposite of that shown in the drawings herein, and additional spirals or lamina may be arranged on the same post, without departing from the spirit of the invention.

It will be observed that the spirals of the lamina contain an infinite number of radii, of different lengths, which are believed to be capable of accommodating an infinite number of tones, and this is believed to be the secret of the numerous overtones and improvement in the tone of the instrument which is secured thereby.

The sound-post and lamina thereon is preferably made of a size to permit of its being turned inwardly through the opening near the bridge of the instrument, and positioned

therein by means of a sound-post setter, specially provided for such purpose. The invention can thereby be applied to instruments already manufactured and in use. In some 5 cases, however, a larger form of the device would be desirable, in which case it could be built into the instrument at the time of construction thereof, or the instrument can be taken apart for the purpose of installing 10 the same therein, and again put together.

It has been demonstrated that the invention conforms to the principles mentioned, and fulfills its functions in a definite and positive manner. It improves the tone of 15 a cheap factory produced violin with a characteristic factory tone to such an extent that the instrument is hardly recognizable. Harmonious result can be attained by faulty and careless bowing of the strings which can not 20 ordinarily be secured on the best instruments.

The position of the sound-post 5 in the violin or other instrument may be varied to suit the particular requirements of the instrument, the same as is done with the sound- 25 posts of a simpler form now in use, and the sound-post set forth herein, with the lamina attached thereto, appears to possess temperamental qualities of its own, such as are commonly found in the stringed instruments 30 themselves.

Better results are secured by positioning

the invention with the straight edge 8 directed toward the neck of the instrument, and in line with the strings thereof.

The same effects that have been set forth 35 herein as being produced by the spiral lamina can be secured to some extent by using independent laminae or disks of varying diameters, spaced apart on the post 5.

What I claim, and desire to secure by Letters Patent, is:

1. A device of the class described, comprising a sound-post adapted for support in the body of a stringed musical instrument, and a lamina wound in a continuous spiral 45 on said post.

2. A device of the class described, comprising a sound-post adapted for support in the body of a stringed musical instrument, and a spiral lamina of gradually increasing radii 50 wound on said sound-post.

3. A device of the class described, comprising a central post support adapted for being positioned between the sounding-board and back of a stringed musical instrument, and a spiral lamina of gradually increasing radii 55 wound thereon, and provided at its widest part with a straight edge projected radially from said support.

In testimony whereof I affix my signature.

RALPH W. STEPHENSON.
